UNITED STATES PATENT OFFICE.

RALPH C. TURNER, OF BELLINGHAM, WASHINGTON.

SPAR-LATHE.

1,295,392.

Specification of Letters Patent. Patented Feb. 25, 1919.

Application filed November 12, 1917. Serial No. 201,679.

To all whom it may concern:

Be it known that I, RALPH C. TURNER, a citizen of the United States, residing at Bellingham, in the county of Whatcom and State of Washington, have invented a new and useful Spar-Lathe, of which the following is a specification.

My invention relates to improvements in spar lathes and the objects of my invention are to provide a lathe which will properly mount, hold and slowly revolve long and large logs from which long spars and masts are made while a revolving cutter is shaping the same, to provide flexible and adjustable guides for the cutter stock and to provide a strong, simple and conveniently operable machine.

I attain these objects by the mechanism illustrated in the accompanying two sheets of drawings in which—

Figure 1 is an end elevation view of the lathe, Fig. 2 is a side elevation view of a portion of the butt end of the lathe, Fig. 3 is a side elevation view of the cutter stock, Fig. 4 is a separated view of the driving mechanism for the butt stock in end elevation drawn on a larger scale, Fig. 5 is a separated view of a portion of the driving mechanism for the cutter stock in sectional end elevation drawn on a larger scale, Fig. 6 is a plan view of the lathe with transverse sections broken away, Fig. 7 is a plan view in diagram of a partly turned mast, in place in the lathe, which is drawn in dotted outline on a smaller scale, and is designed to illustrate the cutter-stock-carriage track adjustment, Fig. 8 is an enlargement of Fig. 1, Fig. 9 is an enlargement of Fig. 3, and Fig. 10 is a separated end-elevation view of one of the cutter-stock-carriage rails and the bar to which it is fastened, drawn in cross section on a larger scale.

Similar characters refer to similar parts in the several views.

Certain parts are broken away in order to show others hidden thereby.

The novel characteristics of my lathe are, the method of mounting and revolving the logs from which spars are made and, the adjustable guideway for the cutter. The former comprises separable rings, each of which is mounted for revolution in a roller cradle and has radial centering and clamping screws. These roller cradles are each mounted on a bolster which is removably clamped to parallel rails or lathe shears.

For the purpose of this description these devices are referred to as roller-cradle stocks. The latter comprises two, light, parallel rails fastened to spacing cross bars which are 60 slidable longitudinally on chafing bars fastened between said shear rails to cross ties. Means are provided to adjust this track to lie in easy curves or straight lines either parallel with or inclined to said shears. The 65 cutter is mounted for revolution on a carriage having flanged wheels to roll on the adjustable track which thus becomes an adjustable guideway for said cutter.

More particularly: 1 is a bolster for the 70 butt roller cradle stock, 1^a is a bolster for the steady-rest roller cradle-stock, 1^b is a bolster for the tail roller cradle stock, 2, 2 are parallel T rails, spiked to cross ties 3, 3, 3, to which said bolsters are fastened 75 by hook bolts 1^c, 1^c, 1^c. 3^a, 3^a, 3^a, are chafing plates fastened to the tops of cross ties 3. 4 and 4^c are two light T rails fastened, in a parallel relation, to slide bars 5, 5, 5. 4^b is a rack fastened to the outside of the web 80 of rail 4. Each of slide bars 5 has an upturned end to form lugs 5^a, 5^a, 5^a. 5^b, 5^b, 5^b are threaded crank rods engaged in tapped holes in the web of one of rails 2. The inner end of each of rods 5^b passes through a 85 hole in one of lugs 5^a which registers with one of said holes through the web of rail 2. Said inner end is engaged to said lug by a set ring 5^c on each side of said lug. The outer end of each of rods 5^b is shaped to 90 form a crank and handle. 6 is the head or butt roller cradle stock, being a ring having an outside toothed rib 6^a, roller surfaces 6^b, 6^b, four radial tapped holes in each of which is engaged a turret headed screw 6^c with a 95 revoluble cap 6^d. Each of said screws is retained by a set nut 6^e. 6^d is a pinion engaged with gear 6^a and is rigidly mounted on shaft 6^e. Shaft 6^e is mounted for revolution in bearing 6^f which is bolted to bolster 1, see 100 Fig. 4. On the other end of shaft 6^e is rigidly mounted drive pulley 6^g. 7 is a steady-rest roller cradle stock, a ring having roller surfaces 7^b, 7^b and four tapped radial holes in each of which is engaged a turret 105 headed screw 6^c. 7^b is the tail roller cradle stock and resembles the steady-rest stock 7 in every respect. Each of stocks 6, 7 and 7^a is mounted on a roller cradle comprising two pairs of rollers 8, 8, etc. Each of rollers 8 is mounted on bearings 8^a fastened on top of one of said bolsters. Each of said

roller cradle stocks is made in two parts bolted together, as shown. 9 is the platform of the cutter stock and has four bearings 9^c fastened to its under side in 5 which are mounted axles 9^e, 9^s of truck wheels 9^b, 9^b, 9^b, 9^b, each having a flange 9^f. Said wheels are mounted on tracks 4, 4^a. 9^c and 9ⁱ are two registering vertical bearings fastened respectively below and above 10 the platform 9. In said bearings is mounted shaft 9^e on the lower end of which is rigidly mounted pinion 9^d engaged with rack 4^b, see Fig. 5. On the upper end of shaft 9^e is bevel gear 9^f having hub 9^a slideable on 15 spline 9^p with which it is engaged. Spline 9^p is inserted in a key seat in shaft 9^e. 9^e is a ratchet having two notches 9^h and 9ⁱ, rigidly connected to bearing 9ⁱ. A yoke 9^r on the lower end of hand lever 9^k is engaged 20 with an annular groove in hub 9^a of gear 9^f. Finger lever 9^m is pivoted to hand lever 9^k and connected by a rod to dog 9ⁿ pivoted to said hand lever where it may engage in either of notches 9^h or 9ⁱ. 9^a is a bearing 25 bracket fastened to the top side of platform 9. 10 is a revolving cutter head mounted on one end of mandrel 10^d. Mandrel 10^d is mounted for revolution in bracket bearing 9^a parallel to tracks 4, 4^a. Four cutters 10^a 30 are fastened to cutter head 10. Cutters 10^a, 10^a, etc., are mounted and adjusted to cause their points of contact with the spar to be vertically over track 4^a. A pulley 10^b is rigidly mounted on mandrel 10^d. 10^c is a 35 worm rigidly mounted on the other end of said mandrel. 11^a is a worm wheel engaged with worm 10^c and rigidly mounted on the upper end of diagonal shaft 11. Shaft 11 is mounted for revolution in bearings 11^b 40 and 11^c fastened to bearing bracket 9^a. 11^a is a bevel gear rigidly attached to the lower end of shaft 11 and engaged with gear 9^f when it is in its upper position shown in Fig. 3. When hand lever 9^k is moved to 45 cause dog 9ⁿ to engage in notch 9ⁱ gear 9^f is moved down on shaft 9^e and on spline 9^p out of engagement with gear 11^a, as usual with such gear shifting devices. 12 is an electric motor, having controller 14, both of which 50 are mounted on cutter stock platform 9. The shaft of said motor has a pulley 12^a in belting relation with pulley 10^b on the cutter head mandrel. Belt 13 transmits power from pulley 12^a to pulley 10^b. In Fig. 7 A 55 is a log rigidly held by screws 6^c in stocks 6, 7, and 7^a for revolution with and by said stocks. From said log the partly completed mast A¹, A², A³ has been turned by cutters 10^a. 60 To operate my lathe, the upper half of each of stocks 6, 7 and 7^a is removed, by aid of a suitable crane, after removing the bolts fastening the parts of said stocks together. The bolsters 1, 1^a, 1^a, on which said stocks 65 are mounted, are fastened to rails 2, 2 with hook bolts 1^c, as described, and relatively placed as shown in dotted outlines in Fig. 7, where the first position of stock 7^a is at 7^{a'}. Log A, suitable for the mast to be turned, is then, by the aid of said crane, 70 placed in the lower halves of said stocks 6, 7 and 7^a, resting on the caps 6^j on the inner ends of those screws 6^c in said lower halves of the roller stocks. The removed parts of the roller stocks are replaced and fastened 75 and screws 6^c are adjusted to bring the longitudinal center line of log A substantially to coincidence with the axis of revolution of said roller stocks. This adjustment is aided by referring to center line a—a which is 80 marked on the floor beneath the lathe, Fig. 7. Track 4, 4^a is adjusted by using crank screw rods 5^b, to bring the inner side of the head of rail 4^a vertically below the front side of part A¹ of said mast. This position 85 is indicated by A^{1'} in Fig. 7. Then tool stock 9 is placed on its track 4, 4^a to the right of log A in Fig. 7. Drive pulley 6^g is caused to revolve by a belt and source of power not shown, and thus head, roller 90 cradle stock 6 is caused to revolve slowly by pinion 6^d. This revolves log A which, in turn, causes roller-cradle stocks 7 and 7^a to revolve. Motor 12 is then started, causing the rapid revolution of cutter head 10, 95 which, in turn, causes the slow movement of the cutter carriage on tracks 4, 4^a through worm gears 10^c, 11^d, bevel gears 11^a, 9^f, and rack and pinion 4^b, 9^d, and the top end of part A¹ of the mast is turned by revolving 100 cutters 10^a. When the tool stock reaches position 9^f, Fig. 7, its further progress leftward is prevented by the tail roller cradle stock at 7^{a'}. Then all power is shut off and tail roller stock is taken from its position at 105 7^{a'} and placed in position 7^{a''}. This is done by first removing the bolts that fasten the two halves of ring 7^a together, lifting off the upper half of said ring, loosening the 110 nuts on hook bolts 1^c, 1^c in bolster 1^b and turning said hooks to the position shown in dotted lines in Fig. 1, and then removing the lower half of ring 7^a and bolster 1^b and setting them up and thus assembling the tail roller stock in position 7^{a''}, Fig. 7, where it 115 will remain to properly hold the top end of the mast until the work of turning it is completed. Turning is resumed and continued until the cutters have reached the hound's shoulder at A³, when power is stopped and 120 tracks 4, 4^a shifted, by using crank screw rods 5^b, to bring the inside surface of the head of rail 4^a in a vertical position below the contour of the line A^{2'}, Fig. 7. Work is again resumed until the tool stock reaches 125 position 9^g where steady-rest stock 7 prevents further movement. Said stock is then removed from its position shown in Fig. 7 and set up to the right of the tool stock after the manner that the tail roller stock was 130

5 moved and set up. Turning again proceeds until the cutters have reached the butt section of the mast when it is stopped and tracks 4, 4^a are shifted to bring the front side of the head of 4^a vertically below the contour of line A³ when turning is resumed and continued until the cutters have reached the butt end of the mast. The surface of the new mast is then finished by the use of sand 10 paper or other proper abrasive applied on the revolving mast. This being completed the top parts of the roller stocks are removed and the completed mast with the butt end of the log attached is taken from the 15 lathe and said butt end cut off when the mast is completed.

20 Tracks 4, 4^a are sufficiently pliable to make them readily adjustable to lie in the contour of any mast or boom stick likely to be desired. The described construction of the 25 log-supporting mechanism is important. The great weight, length and considerable irregularity of the logs make the ordinary means of support for the material operated on insufficient for my objects. My roller-craddle supporting device affords the ease and freedom in turning the log that is essential for the purpose intended.

A greater number of roller stocks than three is used when turning the longer masts. 30 Because of the great weight, length and considerable irregularity of the logs to be turned, above referred to, turret-head screws 6^c are well adapted to adjust, clamp and retain the logs in proper position in the annular head, rest, and tail stocks, as shown. When said screws must bear on finished parts of the mast, blocks of wood are placed between caps 6^d and the mast in order to protect the work from injury. 35 40

Having fully disclosed my invention, what I claim as new and desire to secure by Letters Patent is—

In a spar lathe in combination, two parallel lathe-shear tracks; a plurality of roller 45 cradles movably fastened to said shear tracks adapted to mount the work; a cutter-carriage guideway transversely flexible in a plane parallel with the plane of said shear tracks and having mounted thereon, for longitudinal movement only, a cutter carriage mounting a rotary cutter; and means to adjust said cutter-carriage guideway in curves and tangents thereto in said plane. 50

RALPH C. TURNER.
